(57) **CLAIM**

The ornamental design for a luminaire as shown and described.

DESCRIPTION

FIG. 1 is a top perspective view showing an embodiment of a new design for a luminaire;

FIG. 2 is a bottom perspective view of the luminaire of FIG. 1;

FIG. 3 is a front view of the luminaire of FIG. 1;

FIG. 4 is a rear view of the luminaire of FIG. 1;

FIG. 5 is a right-side view of the luminaire of FIG. 1;

FIG. 6 is a left-side view of the luminaire of FIG. 1;

FIG. 7 is a top view of the luminaire of FIG. 1; and,

FIG. 8 is a bottom view of the luminaire of FIG. 1.

The dashed lines showing portions of the luminaire are included for the purpose of illustrating environment and form no part of the claimed invention.

1 Claim, 6 Drawing Sheets
